(57) CLAIM

The ornamental design for a garment bag, as shown and described.

DESCRIPTION

FIG. 1 is a front perspective view of a garment bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the garment bag, which form no part of the claimed design. The dash-dot-dash broken lines encircling the enlarged views are for annotative purposes only and form no part of the claim thereof.

The thin broken lines on the surface of the garment bag illustrate portions. The thick broken lines in FIGS. 1 and 9 illustrate the location and bounds of the enlarged view. None of the broken lines form part of the claimed design.
